BANNER TOWING MEANS FOR AIRPLANES

Sеле Sidney Pike, Howard Beach, N. Y.

Application October 21, 1938, Serial No. 236,154

1 Claim. (Cl. 40—127)

This invention relates to the towing of aerial advertising banners which are commonly upwards of 100 feet long, with a width of 7 feet or more, and because of their weight and displacement 5 present serious difficulties in the distribution of the stresses at their point, or points, of connection between the forward end of the banner and the tow rope and ropes, and also at the point, or points, of connection between the tow rope or 10 ropes and the fuselage of the airplane.

It is the object of the present invention (a) to provide an improved distribution of stresses at the forward end of the advertising banner; (b) to provide a construction employing two tow cables 15 in such manner that the tow ropes may be led from under the fuselage, one rope in advance of the other, so as to distribute upon the fuselage at spaced points, divided stresses from the advertising banner, and (c) to provide an im- 20 portant safety factor through the employment of two tow cables so connected to the advertising banner that upon the breaking of one tow cable, the banner will not be lost, but will be thrown out of normal operation, tending to rotate and 25 thus visibly attracting the attention of the pilot so that the airplane may be landed to re-establish the towing connection.

The invention will be described with reference to the accompanying drawings, in which:

30 Figure 1 is a view in side elevation of an airplane, showing the connection therewith of an advertising banner, fragmentarily shown, by means of an embodiment of the invention.

Figure 2 is an enlarged side elevation of the 35 airplane tail section to better illustrate the cable-attaching instrumentalities.

Figure 3 is an end elevation of the structure shown in Figure 2, somewhat schematically 40 shown.

45 Figure 4 is a view in elevation showing a banner spreader bar and double tow rope connections with straps forming part of the banner construction leading rearwardly of the bar.

Figure 5 is a view similar to Figure 4, showing 50 a modified form of double tow line connections with the spreader bar.

Figure 6 is a fragmentary longitudinal section on the line 6—6, Figure 2.

Figure 7 is a fragmentary view in elevation of 55 the tow line release bar and release hook construction as employed in Figures 1 and 2.

In the constructions shown in Figures 1 to 3, 6 and 7, the airplane 1 has connected thereto a release hook bar 2 carried by a strong bracket 55 fixed to the tail area of the airplane. The bracket

comprises a saddle frame 3 which is shown in Figure 2 and may be bolted to the tail of the airplane as at the point 3x. Rearwardly projecting from the saddle frame are two frame bars 4 which meet and are secured to the lower end of the vertical release bar 2. To further reinforce the release bar a curved strut or struts 5 may be employed.

At its upper and at its lower ends the release bar 2 carries short bracket arms, one being shown 10 at 6, Figure 7, to which is pivoted a release hook 7 over which is adapted to be thrown a locking yoke 8 when the cable 9 is on the hook. The locking yoke has an eye at its free end to be engaged by cable 10 guided by a pulley 11 down- 15 wardly to a lowermost pulley 12 from which the cable may lead to the cock pit. The lower tow cable 9x is engaged by its release hook 7 which is held by its latching yoke 8, the latching yoke being connected to the cable 10x which may lead 20 over pulley 12 and be either connected to cable 10 or separately led to the cock pit as shown in the drawings.

The advertising banner generally indicated at 13 carries at its forward end the usual rigid 25 spreader bar 14. Three bridle lines shown generally at 15 lead to an eye member 16 to which tow cable 9 is connected. The lowermost of these bridle lines lie substantially above the longitudinal center of the spreader bar 14. Connected to the spreader bar substantially below the longitudinal center thereof are three bridle lines 15x connected to an eye 16x to which the tow cable 9x is, in turn, connected.

By the use of two tow cables in the manner 35 illustrated and described, the stresses at the forward end of the banner are evenly divided, and should one of the tow cables 9 or 9x break, or should any one of the connections for said cable tear loose, the sign will not be lost through its 40 release and the tearing action of wind currents and obstacles in the uncontrolled descent thereof. Instead, the unequal pull upon the spreader bar at an end thereof substantially at one side of the longitudinal center, will cause the sign to 45 slowly "roll", throwing the same out of operation, but calling the pilot's attention to the necessity for landing and reconnecting the deranged tow rope.

While the bracket and release bar arrangement 50 illustrated in Figures 1 to 3 and 6 and 7 is desirable in some cases and where the airplane is so constructed that the added weight of the bracket does not derange the stability of the airplane, there are many cases where the stresses 55

- from the tow cable may be advantageously distributed at a plurality of points on the fuselage, and therefore the cables 9 and 9x may be led under the fuselage to release hooks which may, 5 for example, be positioned one slightly back of the cockpit, and one at the tail of the ship. Also, the two tow cables may be led to a single point of the fuselage and to a single release hook or two adjacent release hooks.
- 10 In the modification illustrated in Figure 5, the tow cables 9 and 9x are connected to the spreader bar 14, each through the instrumentality of two bridle lines 17, 18, leading to the eye members 16, 16x, and by a bridle line 19 which extends continuously from eye member 16 to an eye bracket 20 on the spreader bar at the longitudinal center thereof, and thence to eye member 16x. In this modification, the breaking of either of the tow cables 9 or 9x will cause a more rapid 20 "roll" of the banner and such a fluttering and

audible signal effect to the pilot that he will very quickly be informed by such safety factor, that it is necessary to land and re-establish the proper connections.

Having described my invention, what I claim 5 and desire to secure by Letters Patent, is as follows:

In banner towing means for airplanes in combination with an advertising banner and a spreader bar carried thereby at its forward end 10 of two towing cables adapted for connection with an airplane fuselage, a bridle line connecting each cable with the spreader bar at a point near an end thereof, and a second bridle line leading from the end of one towing cable to the end of 15 the second towing cable and loosely passed through an eye member carried by the spreader bar at approximately its longitudinal center.

SELE SIDNEY PIKE. 20
